UNITED STATES PATENT OFFICE.

ERNEST A. EASTMAN, OF CHICAGO, ILLINOIS, ASSIGNOR OF ONE-HALF TO CRAWFORD McGREGOR & CANBY COMPANY, OF DAYTON, OHIO, A CORPORATION.

LAST-DEMONSTRATOR.

No. 882,818.

Specification of Letters Patent. Patented March 24, 1908.

Application filed October 29, 1907. Serial No. 399,650.

To all whom it may concern:

Be it known that I, ERNEST A. EASTMAN, a citizen of the United States, residing at Chicago, in the county of Cook and State of Illinois, have invented an Improvement in 5 Last-Demonstrators, of which the following description, in connection with the accompanying drawings, is a specification, like letters on the drawings representing like 10 parts.

My present invention is a device for demonstrating or designating to the observer the position which the axis of the foot will be compelled to occupy by a given heel, 15 being a species of the invention covered generically in my copending application Ser. No. 386,730 filed August 2, 1907, where the invention, broadly considered, is more fully described, said application and my present 20 application both having reference also to my invention set forth in Patent No. 857,552 of June 18, 1907.

In carrying out my present invention I provide, in connection with a sole member (or 25 piece cut like a sole pattern or innersole), an upwardly extending part shaped to conform exactly to the heel, said part being limited in its extent to the heel portion so as to leave the entire sole-part free and unrestricted for 30 the purpose of visually indicating to the observer the position which the given heel will compel the axis of the foot to occupy in a shoe constructed according to the pattern or outline of said sole-part. This upwardly 35 extending portion may either be secured permanently to the sole-part of the demonstrator or detachably, the former rendering the demonstrator better adapted for demonstrating in connection with the actual foot of 40 an interested party, while the latter is more convenient for visually comparing different sole patterns or styles of lasts.

In the drawings, in which I have shown two preferred embodiments of my invention, 45 Figure 1 is a plan view of one form of the demonstrator, Figs. 2 and 3 are plan views of another form of the demonstrator; Fig. 4 is a fragmentary view in side elevation of the embodiment of my invention shown in Figs. 50 2 and 3, looking at the rear or heel end thereof; and Fig. 5 is a cross sectional view on the line 5—5 Fig. 1.

As illustrated in Figs. 1 and 5, the demonstrator consists of a base or back 1 which

may be of wood cardboard, celluloid, metal 55 or any suitable durable substance, to which is secured a plate 2 preferably of hard metal, such as steel, so as not to wear appreciably in use, and sole parts 3 3^X, herein shown as two in number. The part 1 is flat so as properly 60 to display the parts 3 3^X, when placed thereon, and the part 2 is accurately cut away in its front edge so as to provide a vertical wall 4 conforming with the utmost nicety and exactness to the standard heel contour or outline to the 65 sole-parts 3 3^X and for receiving the same as clearly shown in Figs. 1 and 5. A thumbscrew or other securing means 5, herein shown as having a threaded end 6 securing into a ferrule 7 in the base 1, is provided for centrally clamp- 70 ing the sole-parts 3 3^X, which for this purpose are centrally apertured at 8.

In the construction shown in Figs. 2 and 3 the same sole-parts 3 3^X are provided, but instead of having the vertical wall 4 75 formed in a metal or other plate 2 separately secured on a base or back 1 I form the same directly on the sole-part as indicated at 9, where I have shown a vertical portion, extending upwardly approximately coexten- 80 sively with the usual shoe counter, and bent under the sole-part 3 3^X about its heel contour or outline, where it is secured permanently to the sole-part as indicated by dotted lines at 10. Preferably each sole- 85 part contains an axis line 11 marking the center line of the last as explained in my above mentioned Patent No. 857,552, and in the form of my invention shown in Fig. 1 the base 1 also contains the same line as indicated at 12.

In use let it be supposed that it is desired to demonstrate the advantages of my particular kind of last, *i. e.*, the last of my patent last mentioned, over the same style of 95 crooked last provided with the ordinary or old-kind of heel, the two bottom-patterns of the respective lasts are reproduced in correspondingly shaped sole-parts, the one showing my patented last being indicated at 13 100 and the other at 14 in the drawings. The operator or user then places one sole-part on the other so that the vertical wall 4, Fig. 1, or walls 9, Figs. 2 and 3, compel the heel-parts of the two different styles of sole-parts 105 to coincide one above the other, the result being that the forward portions of the two sole-parts are caused to assume the relative

positions shown in Fig. 1, thereby bringing the axis lines 11 thereof vertically over each other, and, when using the demonstrator of Fig. 1, in line with the line 12 of the base 1. 5 One advantage of having each sole-part provided with its own thin peripheral vertical wall as in Figs. 2 and 3, instead of having said wall provided separately as in Fig. 1, is that it enables the operator to use the demonstrator directly on the foot of an interested party, simply by shoving the demonstrator, Fig. 2 or Fig. 3, against the sole of the foot, thereby causing the wall portion 9 to embrace the heel of the foot. This causes the 10 demonstrator to assume, with relation to the foot, the actual position of the shoe, which is shown more accurately in Fig. 1, the form of sole-part in Fig. 2 projecting beyond the foot on the forward inside part, whereas the form 15 shown in Fig. 3 follows the shape of a normal foot without projecting at any portion thereof. Instead of merely indicating the relative position of the center line, as by the bar of my above mentioned application, in my 20 present embodiment of the invention I provide the entire sole-part and show tangibly and visually how the different heel contours or outlines compel said sole-part to swing to one side or the other and hence the trend of 25 the corresponding last or shoe, the center line thereof being indicated by the marked line 11 and 12. This illustrates to the unskilled the effect which the shifting of the heel outline or contour laterally in one direction or the other will have on the position of 30 the foot in the shoe when made, thereby enabling the average wearer of shoes to appreciate such variations or differences in the lines of the heel prior to getting the corresponding shoe actually on his foot. 35

Having described my invention, what I claim as new, and desire to secure by Letters Patent, is,

1. A device for the purpose set forth, comprising means showing the outline of a forepart, and means showing the outline of a heel part, including means for showing varying positions of the heelpart outline with relation to the forepart outline consisting of a 45 plurality of sole-parts having their forward portion arranged at varying directions with relation to the same heel contour, and means for compelling the corresponding heelpart contours to substantially coincide when said 50 sole-parts are superposed.

2. A device for the purpose set forth, comprising a sole-part whose forepart terminates free and unrestricted at its edge-boundaries which have the peripheral outline of the in-

sole of a shoe, and a vertical wall conforming 60 in outline to the contour of the heel portion of said sole-part.

3. A device for the purpose set forth, comprising a sole-part having the peripheral outline of the insole of a shoe, and a base for receiving said sole-part provided with a vertical wall conforming in outline to the contour of the heel portion of said sole-part. 65

4. A device for the purpose set forth, comprising a sole-part having the peripheral outline of the insole of a shoe, a separable wall conforming to the outline of the heel part thereof, and means for detachably positioning said heel-part in exact engagement with said wall. 70

5. A device for the purpose set forth, comprising a sole-part having the peripheral outline of the insole of a shoe, a vertical wall conforming in outline to the contour of the heel portion of said sole-part, and means for indicating visually the axis line of said sole-part with relation to said wall and heel portion. 75

6. A device for the purpose set forth, consisting of a plurality of sole-parts all having the same heel outline but in different relative 80 positions with relation to the fore-parts thereof, and means for automatically alining said heel outlines when said sole-parts are placed on top of each other.

7. A device for the purpose set forth, consisting of a plurality of sole-parts all having the same heel outline but in different relative positions with relation to the foreparts thereof, a plane base for supporting said sole-parts, a vertical wall secured at one end of 90 said base conforming to said outline, and means for positioning all of said sole-parts so as to make their heel outline coincide against said wall. 95

8. A device for the purpose set forth, consisting of a plurality of sole-parts all having the same heel outline but in different relative positions with relation to the foreparts thereof, all of said sole-parts being similarly apertured in their heel-parts, a base for supporting the heel ends of said sole-parts, a vertical wall projecting from said base, and clamping means arranged to extend through said apertures to clamp said sole-parts to said base with their heel outlines coinciding 105 against said wall. 110

In testimony whereof, I have signed my name to this specification, in the presence of two subscribing witnesses.

ERNEST A. EASTMAN.
